(57) **CLAIM**

The ornamental design for a light emitting anisotropic lens, as shown and described.

DESCRIPTION

1. Light emitting anisotropic lens
1.1 : Perspective
1.2 : Front
1.3 : Back
1.4 : Left
1.5 : Right
1.6 : Top
1.7 : Bottom
1.8 is a cross-section of the light emitting anisotropic lens, taken along the line A-A' of 1.3.
The combination of form and shape of the "light emitting anisotropic lens" is the gist of the design; the dash dot lines and letter A A' in the back view indicate the position where the cross-sectional view 1.8.
